UNITED STATES PATENT OFFICE.

MARSENA R. JULIAN, OF CINCINNATI, OHIO, MARK H. HOVEY, OF MADISON, WISCONSIN, AND THOMAS E. CLARK, OF DETROIT, MICHIGAN, ASSIGNEES TO JULIAN-BEGGS SIGNAL COMPANY, OF TERRE HAUTE, INDIANA, A CORPORATION OF MAINE.

BLOCK-SIGNAL SYSTEM.

1,267,771.

Specification of Letters Patent. Patented May 28, 1918.

Application filed April 22, 1915. Serial No. 23,273.

To all whom it may concern:

Be it known that we, MARSENA R. JULIAN, of Cincinnati, in the county of Hamilton and State of Ohio, MARK H. HOVEY, of Madison, in the county of Dane and State of Wisconsin, and THOMAS E. CLARK, of Detroit, in the county of Wayne and State of Michigan, all citizens of the United States, have invented certain new and useful Improvements in Block-Signal Systems, of which the following is a specification.

Our invention relates to block signal systems for railways and more particularly to the various engine cab mechanisms and their circuits. The primary object of our invention is the provision of a block signal system which will fully come up to the present day railroad requirements that any possible failure, of any circuit or mechanism, of either the track system or cab system gives the most unfavorable signal for which the system is designed.

One highly important object of our invention consists, therefore, in the provision of a system in which a danger warning signal will be given at the entry of each block through the opening of a mechanical circuit breaker in a normally closed cab circuit.

In this connection, a still further object which we have in mind is the provision of means such that unless, due to the condition of the block, the danger signal is the proper one, said signal will be immediately followed by the proper signal, such as a caution signal or a clear signal. In furtherance of the above object, we so arrange the wiring of the cab system that a caution signal or clear signal can be given only by completing a circuit through portions of the cab and track systems, the source of energy for such circuit being located in the track system in order that such a signal can be given only if the track system is in perfect order. This arrangement, therefore, tests the track system. More specifically, our system, in its preferred embodiment, is designed to, under proper circumstances, give, in addition to the danger signal, either a caution signal or a clear signal for the direction and guidance of the engineer.

Our invention has for a still further object the provision of a system in which the receipt of a danger signal will, unless immediately followed by a clear or caution signal,

automatically stop the train, even though the engineer wishes to proceed. The mere stopping of the train upon receipt of a danger signal is, however, not enough as, if the driving of the train is left wholly to the discretion of the engineer, aside from this feature, he may drive the train at a dangerous speed upon clear tracks or when running under a caution signal or he may, if the train has been completely stopped for a danger signal, upon again starting, proceed at a speed which is dangerous under the conditions indicated by the signal.

A still further object of our invention, therefore, consists in the provision of a speed controlling or governing mechanism which shall operate in connection with the signaling mechanism and which shall absolutely fix the maximum speeds at which the train may travel under different circumstances. For instance, this speed controlling mechanism may be so set that it will be impossible to run the locomotive at a speed of over fifty miles an hour, under any circumstances; that it will be impossible to run the train at a speed of over twenty-five miles an hour when running under a caution signal; and that it will be impossible to run the train at a speed of over five miles an hour when running under a danger signal.

As previously pointed out, a danger signal is received at the entrance of each block and this danger signal, unless immediately followed by some other signal, will automatically bring the train to a stop.

A further object of our invention is to provide means, in connection with the speed controlling mechanism, whereby the train, after being brought to a dead stop by the receipt of a danger signal, may be started again and run under the danger signal at the minimum rate of speed for which the system is adjusted. This means, however, is manually operated and it is, therefore, impossible for the train, of its own accord, to start after receiving a danger signal, thereby avoiding any possibility of accidents which might otherwise occur upon stopping and starting of a train, the engineer of which was temporarily incapacitated.

A still further object of our invention consists in the provision of means whereby any failure in the operation of the speed controlling mechanism will automatically stop

the train. This also prevents an engineer from tampering with the speed controlling mechanism as any disconnecting of such mechanism will prevent running of the train until the mechanism has been properly readjusted and put in working order.

A still further object of our present invention consists in interposing a pole changer in one of the main circuits of the cab system 10 in such a manner that the contact members, employed to give the clear and caution signals, may be interchanged by merely shifting the pole changer. Under these circumstances, the same clear and caution contact 15 shoes may be employed with the same track contacts when the train is being backed through a block, that shoe which ordinarily forms the clear shoe, when the train is proceeding in a normal manner, forming the 20 caution shoe when the train is backing, while that shoe which is normally the caution shoe becomes the clear shoe. This pole changer is, preferably, connected to the reversing lever of the locomotive, for which reason its 25 operation is automatically insured.

A still further object of our invention is to provide a signal system capable of accomplishing the above given results which shall be extremely simple in construction and economical in installation.

With these and other objects in view, our invention will be more fully described, illustrated in the accompanying drawings, and then specifically pointed out in the claims 25 which are attached to and form a part of this application.

In the drawings:

Figure 1 is a diagrammatic view of the cab mechanisms and wiring of our improved 40 block signal system, this view also showing a slight portion of the track wiring in order to fully disclose the manner of operation of our invention;

Fig. 2 is a side elevation of one of the 45 contact shoes carried by the locomotive or its tender;

Fig. 3 is a sectional view, illustrating one 50 of the mechanical circuit breakers carried by the locomotive or its tender;

Fig. 4 is a sectional view, illustrating one 55 of the mechanical circuit breakers or track contacts and its contact member, these circuit breakers or track contacts being disposed adjacent the track rails for engagement by the contact shoes of the locomotive.

Fig. 5 is a diagrammatic view of a conventional track wiring system employing polarized relays, which may be employed with our cab system, three complete blocks being 60 shown.

Corresponding and like parts are referred to in the following description and indicated in all the views of the drawings by the same reference characters.

65 In order to insure a clear and complete

understanding of our invention, we will first describe, in its simplest form, that portion of the track signal mechanism and contacts which directly controls the cab circuits and their mechanism although the latter alone 70 constitute the subject matter of our present invention. Referring to Fig. 1, *a* indicates the trip or track obstacle for operating the mechanical circuit breaker carried by the train, and *b* and *c* the clear and caution 75 track contacts which are engaged by the clear and caution contact shoes carried by the train. Preferably, the contacts *b* and *c* are disposed one at either side of the track and outside of the rails, as shown, while the 80 obstacle *a* is located near one of these contacts.

The construction and operation of the track obstacle *a* will be readily appreciated from its diagrammatic showing and reference to Fig. 4 of the drawings will disclose the construction and manner of operation of the track contacts *b* and *c*. In this figure, 10 indicates a casing in which is journaled a shaft 11 provided exteriorly of the casing 90 with an upwardly directed contact arm 12. Within the casing, the shaft is provided with diametrically opposed ears 13 and springs 14 connect these ears with opposite end portions of the casing or housing, the arrangement of 95 ears and springs being such as to normally hold the contact arm 12 in vertical position and to return it to such position after it has been swung either forwardly or rearwardly by engagement with a cab carried contact 100 shoe. The shaft carries a sleeve 15 of vulcanized rubber, fiber or other suitable insulating material and mounted upon this sleeve is a peripherally extending contact 16 which is electrically connected to the shaft 11 and, 105 consequently, to the contact arm 12. The shaft and its arm are thoroughly insulated, in any suitable manner, from the housing as also is a spring contact finger or brush 17 mounted in the housing to engage at its free 110 end with the sleeve 15 or contact 16, depending upon the position of the contact arm 12. Under normal conditions, that is, when the arm 12 is vertically disposed, the contacts 16 and 17 are out of engagement with each 115 other. Furthermore, swinging of the contact arm 12 in one direction will have no effect, the contacts still remaining out of engagement. On the other hand, swinging of the arm 12 in the opposite direction will 120 bring the contacts into engagement with each other. The track contact *b* is so arranged that if its contact arm is engaged by a contact shoe carried by a train going toward the right and, consequently, swung toward 125 the right, its contacts 16 and 17 will engage each other. The contact *c* is similarly arranged to be operated by a train passing toward the right.

Co-acting with each pair of track contacts 130

b and *c* are a pair of switches *d* and *e* which are controlled by trains passing over the track through circuits formed through the track system. As this control system forms 5 no part of this invention, we will not describe it but merely state that, as a rule, the moving contacts of these switches are in fact moving points of relays in the track circuits and that each switch is movable into 10 three positions, both switches moving simultaneously. As shown in Fig. 1, the switches are in position to give a clear signal and by swinging them in a clockwise direction, until the switch *e* is closed, they may be 15 brought into position to give a caution signal. Upon further swinging movement in the same direction to open both switches, no signal will be given, the result being, as will be later explained, the giving of a danger 20 signal by the cab system itself.

A storage battery *f*, or other suitable source of electrical energy, is grounded to one of the track rails by a conductor *g* and a wire *h* leads from this battery to the fixed 25 contact of the switch *d*. A wire *k* leads from the swinging contact of this switch to the contact 17 of the switch contact *b*. A wire *m* leads from the wire *h* to the fixed contact of the switch *e* and a wire 30 *n* leads from the movable contact of this switch to the contact 17 of the track contact *c*.

In the preferred embodiment of our invention, as disclosed in Fig. 1, each train 35 is equipped with a pair of mechanical circuit breakers *A* and *A'* and a pair of contact shoes *B* and *C*. These parts are usually mounted upon one of the wheel trucks, preferably one of the wheel trucks of either the 40 locomotive or its tender as a locomotive and tender always form one part of every train. Reference to the drawings will show that the truck, conventionally indicated at 20, assuming that it is going toward the right, 45 is provided adjacent its forward end and upon its right side with the circuit breaker *A* and adjacent its rear end and upon its left side with the circuit breaker *A'*. The contact shoes *B* and *C* extend longitudinally 50 along the sides of the truck, being insulated therefrom, in position to engage and swing the contact arms of the track contacts *b* and *c*. The contact shoes, which are preferably formed of resilient metal with downwardly 55 bowed central portions, are clearly enough shown in Fig. 2 to insure an understanding of their operation.

The construction of the circuit breakers *A* and *A'* is clearly shown in Fig. 3 of the 60 drawings. In this figure, 21 indicates the casing or housing in which is journaled a vertically disposed shaft 22. This shaft is provided at one end and exteriorly of the housing with a laterally directed arm 23 65 and interiorly of the housing with an ear

24. A helical spring 25 is connected at one end to this ear and at its other end to the housing in such a manner as to normally hold the shaft with its arm 23 extending at right angles from the truck and to return 70 the arm to such position immediately after it has been released from engagement with any track obstacle or trip. This shaft carries a sleeve 26 of insulating material which, in turn, carries a peripherally extending contact plate 27, this contact, in this instance, being totally insulated from the shaft 22. Mounted in the casing and insulated therefrom are spring contact fingers 28 which normally engage the contact plate 27. The contact plate 27 is so proportioned and disposed that swinging of the arm 23, in one direction, will break the connection between the contacts 27 and 28, while swinging 80 of the arm in the opposite direction will not move the contacts out of engagement with each other. The circuit breaker *A* is so disposed that rearward swinging of its arm 23 will break the connection between the contacts 27 and 28, while the circuit breaker 90 *A'* is so disposed that engagement between its contacts will be broken only by swinging of its arm 23 in the opposite direction.

The track obstacle, track contacts, train carried circuit breakers and train carried 95 contact shoes are so arranged relative to each other that upon entering a block, one of the circuit breakers will engage a track obstacle before either of the contact shoes engages a track contact. They are further 100 so arranged that the contact shoes will engage their track contacts almost immediately after the circuit breaker has engaged the track obstacle and will remain in engagement with such track contacts for a short 105 time after the circuit breaker has passed out of engagement with the track obstacle. It will of course be understood that each block will be provided at each end with a track obstacle and with contactors or shoes, 110 those at one end of the block operating for trains going in one direction and those at the other end of the block for trains going in the opposite direction. It will, therefore, 115 be clear that the track obstacles at opposite ends of the block will be disposed upon opposite sides of the track and that the track contacts *B* and *C*, if disposed at the right and left side of the track, respectively, at one end of the block, will be disposed at the 120 left and right sides at the other end. It will, of course, be understood that by proper positioning of obstacles and track contacts, a double track may be equipped as well as a single one.

In addition to the above mentioned structure, each locomotive is provided with a speedometer *D*. By the term "speedometer" we intend to include any mechanism having an element which is shiftable in one direction 125 130

upon increase in speed of the train, the extent of its movement being relative to the increase in speed and which is likewise shiftable in another direction upon a decrease in speed. In the type of speedometer diagrammatically indicated at 21, the movable element consists of a swingingly mounted contact blade or pointer 30 which, when the train is still, engages with a fixed contact 31 and contact strips 32, 33 and 34. When the train is in motion, this pointer swings out of engagement with the contact 31, remaining in engagement with the contact strips until the speed of the train has reached a certain point when it will move out of engagement with the contact strip 32, still remaining in engagement with the other contact strips until the speed reaches a certain further predetermined point when it will move out of engagement with all contact strips, save the contact strips 34. Upon still further increase of speed, beyond a certain point, the pointer will move out of engagement with this latter strip 34. In practice, these strips are adjustably mounted in order to permit variations in the speeds at which the pointer will move out of engagement with them. This speedometer may be driven in any suitable manner from one of the axles of a locomotive truck, as for instance, by means of a metallic belt or chain 36 having a belt tightener 36.

Inserted in the air brake line of each locomotive is an electrically controlled air valve 35 of any suitable type so formed as to be held in closed position as long as a current passes through its controlling mechanism. The details of construction of the speedometer and air valve with its controlling mechanism form no part of the present invention and are therefore merely conventionally shown in the diagrammatic view of our system.

Having thus described the various mechanisms included in our cab signal system, we will now explain the wiring of the various circuits forming the system. Each locomotive equipment includes three relays 40, 41 and 42 which will hereafter be termed the clear relay, caution relay and pick up relay respectively. Each of these relays, as will be rendered apparent by further description of the wiring, is of the stick relay type, the relay 40 being normally energized and the relays 41 and 42 deenergized. The relay 40 controls the relay points 40^a, 40^b and 40^c, the relay 41 controls the relay points 41^a, 41^b and 41^c, and the relay 42 controls the relay points 42^a and 42^b.

Each locomotive carries a storage battery 43 or other suitable source of electrical energy which is grounded at 44 by a wire 45. A wire 46 leads from the battery 43 to one of the contacts of the circuit breaker A', a wire 47 leads from the other contact of this

circuit breaker to one of the contacts of the circuit breaker A and a wire 48 leads from the other contact of the circuit breaker A to the relay point 41^a. This relay point 41^a, in normal, deenergized condition of the relay 41, engages one end of a wire 49 which leads to the relay point 40^a of the relay 40. This relay point 40^a, in normal, energized condition of the relay 40, engages the terminal of a wire 50 which leads to the magnet of the relay 40 and a wire 51 leads from this magnet to the ground wire 45.

A wire 52 leads from the wire 50 to the blade 53 of a pole changer 54. This pole changer includes the blades 53 and 55 and the contacts 56, 57 and 58, the contacts 57 and 58 being electrically connected by a wire 59. A wire 60 leads from the contact 57, and consequently also from the contact 58 to the contact shoe B, while a wire 61 leads from the contact 56 to the contact shoe C. A wire 62 leads from the blade 55 of the pole changer 54 to the magnet of the relay 41 and a wire 63 leads from this magnet to the ground wire 45 and so to the common ground 44.

A wire 64 leads from the wire 46 to the relay point 40^b of the relay 40, this relay point being electrically connected with the relay point 40^c by a wire 65. In normal condition of the relay 40, the relay point 40^b engages one end of a wire 66 which leads to the contact strip 34 of the speedometer, while the relay point 40^c engages one end of a wire 67 which leads to a signal light 68, a wire 69 leading from this light to the wire 63 and therefore grounding the circuit. The light 68 is preferably a white light as it indicates a clear condition of the block, as will be later explained.

When the relay 40 is deenergized, the relay point 40^b engages one end of a wire 70 which leads to the relay point 41^b of the relay 41. This relay point 41^b, in normal deenergized condition of the relay 41, engages one end of a wire 71 which leads to a light 72, a wire 73 leading from this light to the wire 69. This light 72 constitutes the danger light, as will be later explained, and is preferably a red light.

In deenergized condition of the relay 40, the relay point 40^c engages one end of a wire 74 which leads to the relay point 41^c of the relay 41. This relay point 41^c, in energized condition of the relay 41, engages one end of a wire 75 which leads to a light 76, a wire 77 leading from this light to the wire 69. This light 76 constitutes the caution signal light and is preferably green. Again, in energized condition of the relay 41, its relay point 41^a engages one end of a wire 78 which leads to the wire 62, while the relay point 41^b engages one end of a wire 79 which leads to the caution contact strip 33 of the speedometer.

10*

115

130

- A wire 80 leads from the wire 71 to the magnet of the relay 42 and a wire 81 leads from this magnet to one contact of a manually operable, normally open circuit closer 82. A wire 83, which includes a resistance coil, leads from the other contact of this circuit closer 82 to the contact 31 of the speedometer. A wire 84 leads from the movable arm or blade 30 of the speedometer 10 to the electrical control mechanism of the air valve E and a wire 85 leads from this electrical mechanism to the belt tightener 36 and, consequently, through the belt and car truck to the rails which constitute a ground.
- 15 A wire 86 leads from the wire 81 to the relay point 42^a of the relay 42 and this relay point, when the relay 42 is energized, engages one end of a wire 87 leading to the ground return wire 63. A wire 88 leads 20 from the wire 64 to the relay point 42^b and this relay point 42^b, when the relay 42 is energized, contacts with one end of a wire 89 which leads to the contact strip 32 of the speedometer.
- 25 Before describing the operation of our system, we will say that the track wiring shown is in condition to give a clear signal to a train passing into the block from the left and that the cab wiring and mechanisms 30 are as they would be after receipt of a clear signal. As will be seen by referring to the diagram, when the train is running under a clear signal, a circuit is formed from the battery 43, through the wire 46, circuit breaker A', wire 47, circuit breaker A, wire 48, relay point 41^a, wire 49, relay point 40^a, wire 50, relay magnet 40, wire 51 and wire 45 to the battery. This circuit energizes the relay 40 which is the clear relay of the system. With this relay 40 energized, a circuit is formed from the battery 43 through the wire 64, relay point 40^b, wire 66, contact strip 34, contact blade 30, wire 84, air valve mechanism E, wire 85 and belt tightener 36 45 to the ground, the battery 43 being grounded by the wire 45. Any break of any wire in this circuit will deenergize the valve controlling mechanism E and apply the brakes, as also will the displacement or breaking of 50 the drive belt 35. At the same time this circuit is formed, a second circuit is formed from the battery 43 through the wire 64, wire 65, relay point 40^c, wire 67, clear light 68 and wire 69 to the wire 63 and so back to 55 the battery by the wire 45.
- With the train running on a clear signal, as above described, the supply of current to the contacts 33, 32 and 31 of the speedometer, is cut off by the condition of the relay 60 41, relay 42 and manually operable switch 82, respectively. The contact strip 34, therefore, controls the speed at which the train may travel and if this speed becomes so high that the switch 30 moves from this contact, the valve controlling circuit will be
- opened and the brakes applied. This will not, however, affect the condition of any of the relays and it will, therefore, be clear that as soon as the speed of the train has been brought down to the limit set for it by 70 the contact strip 34, the valve will again close and the train may continue along the track.
- We will now assume that with both the cab and track systems as shown, the train 75 enters a clear block. At its point of entry into the block, its circuit breaker A engages the track contact *a* and the circuit from the battery 43, through the wire 46, circuit breaker A', wire 47, circuit breaker A, wire 80 48, relay point 41^a, wire 49, relay point 40^a, wire 50, relay magnet 40, wire 51 and wire 45 to the battery is broken at the circuit breaker A. The breaking of this circuit deenergizes the relay 40 without energizing 85 either the relay 41 or relay 42.
- Under these conditions, the circuit from the battery 43 through the relay point 40^b to the speedometer is broken between the relay point 40^b and the wire 66, the result, of 90 course, being an application of the brakes. Furthermore, the circuit from the battery 43, through the relay point 40^c to the clear light 68, is broken between the relay point 40^c and wire 67, while a circuit from the 95 battery through the relay point 40^b, relay point 41^b and danger light 72 is closed. It will, therefore, be seen that the danger light will be displayed and the train brought to a stop unless another signal is received. 100
- Proceeding on the original assumption that the block is clear, the danger signal, above described, will no sooner have been given than the contact shoe B will engage the track contact *b*. Under these circumstances, a circuit is formed from the grounded battery *f* of the track circuit through the wire *h*, switch *d* and wire *k* to the track contact *b* from the arm of this track contact to the clear shoe B through 110 the wire 60, wire 52, relay magnet 40, wire 51 and wire 45 to the ground 44. This circuit energizes the relay magnet 40 and holds such relay closed until the circuit is broken. As previously explained, however, 115 the circuit breaker A' is disengaged from its obstacle *a* before the contact shoe B moves out of engagement with the track contact *b*. It will, therefore, be clear that before the circuit from the battery of the 120 track system through the relay 40 is broken, the original circuit from the cab battery 43 through this relay will have again been closed.
- It should be noted that, under ordinary 125 conditions, if the block is set for a clear signal, this signal will follow so rapidly upon the danger signal that the progress of the train will in no way be checked although the white light will momentarily deener-

gized and the red light energized. In other words, the danger signal will merely be a sufficient signal to indicate the fact that the block signal system, as a whole, is operating properly. Failure to obtain this signal is, in itself, a signal of danger, indicating that the track obstacle or mechanical circuit breaker A has been broken or disarranged.

We will now assume that the train passes from a clear block into a block which is set to give the caution signal, that is, one in which the switch d is open and the switch e closed. Under these conditions, the danger signal is given in the manner previously explained, this signal being always given at the entry of every block. Immediately after the giving of this danger signal, however, the contact shoe C, which is the caution shoe, engages the caution track contact c. Under these conditions, a circuit is formed from the grounded track battery f through the wires h and m to the switch e and through the wire n to the track contact c. From this track contact, current passes through the contact shoe C, wire 61, wire 62 and wire 63 to the wire 45 and so to the ground. This circuit energizes the caution relay 41 without in any way affecting the now deenergized relays 40 and 42. While the above circuit is energized, the circuit breaker A moves out of engagement with the track obstacle a and a local cab circuit is formed from the battery 43 through the wire 46, circuit breaker A', wire 47, circuit breaker A, wire 48, relay point 41^a, wire 78, wire 62, relay magnet 41 and wire 63 to the wire 45 and so to the battery 43. As long as this circuit is complete, the relay 41 will be held in closed position and this circuit will exist until another signal of some nature is received. Under these circumstances, a local cab circuit is formed from the battery 43, through the wire 64, relay point 40^b, wire 70, relay point 41^b, wire 79 and contact strip 33 of the speedometer, from the speedometer through the wire 84 and valve mechanism to the wire 85 and so to the ground. This renders the caution contact strip 33 of the speedometer mechanism active and the air valve will remain closed as long as the speed of the train remains below the point set as a maximum speed when traveling under a caution signal.

At the same time, a second local cab circuit is formed from the battery 43, through the wires 64 and 65, relay point 40^c, wire 74, relay point 41^c, wire 75, caution light 76, wire 69, wire 63 and wire 45 to the battery. The extinguishing of the white light and lighting of this green light, of course, indicates to the engineer that he is traveling under a caution signal and he may, therefore, if he deems it advisable, reduce the speed of the train even below that for

which the speed controlling mechanism is set. Of course, as soon as the train enters the next block, the danger signal will be repeated and the train may then receive either the danger signal alone or a clear signal or a caution signal, depending upon the condition of the block which the train is entering.

Assuming that the train is entering a block for which the danger signal is set and, consequently, that both the switches d and e of that block are open, the main controlling circuit will, of course, be broken through the circuit breaker A, as previously described. No circuits, however, will be formed either through the clear relay 40 or caution relay 41, there being no current flowing from the track battery f to either of the track contacts b and c. Under these conditions, the train will be brought to a dead stop and can be started only by an intentional act upon the part of the engineer. When so stopped, the engineer may, if he wishes to continue, momentarily close the manually operable switch 82. Upon closing of this switch, a circuit is formed from the grounded cab battery 43, through the wire 64, relay point 40^b, wire 70, relay point 41^b, wire 71 and wire 80 to the relay magnet 42, through the wire 81, switch 82, wire 83 and its resistance coil to the contact 31 of the speedometer, through the wire 84 and valve mechanism to the wire 85 and so to the ground. The closing of this circuit energizes the relay 42 and also closes the valve controlling the air brakes. As soon as this circuit is closed, a portion of the current passes from the wire 81 through the relay point 42^a, wire 87, wire 63 and wire 45 to the battery, which circuit also energizes the relay 42. For this reason, the engineer may immediately release the switch 82 and the circuit through the relay 42 will remain closed. The energizing of this relay results in a closed circuit from the battery 43, through the wire 64, wire 88, relay point 42^b, wire 89 to the danger strip 32 of the speedometer and from the speedometer through the wire 84, valve mechanism and wire 85 to the ground. The train may, therefore, be driven at any rate of speed below that for which the danger contact strip is set.

As soon as the circuit, which includes the wire 80, relay magnet 42, wire 81, switch 82, wire 83, contact 31, wire 84 and valve mechanism and wire 85, is closed, there is a tendency for a short circuit to be formed from the battery 43, through the wire 64, wire 88, relay point 42^b, wire 89, contact strip 32, contact blade 30, wire 83, switch 82, wire 81, wire 86, relay point 42^a, wire 87 and wires 63 and 45 to the battery. This circuit would tend to prevent proper energization of the relay magnet 42 and it is

for this reason that we have inserted the resistance coil in the wire 83, this coil preventing the setting up of the short circuit above outlined and so insuring proper energization of the relay magnet 42.

It will of course be understood that, as is usual in the track wiring of block signal systems, a track obstacle and clear and caution track contacts will be positioned at each 10 end of each block in order to operate with trains going in either direction, the caution contact and the clear contact and obstacle being located reversely at opposite ends of the block. For this reason, the above described cab signal system will operate in identically the same manner if the locomotive is being reversed through one or more blocks as the movement of the reversing lever will cause operation of the pole changer 15 54, under which circumstances, that shoe B which is ordinarily the clear shoe will become the caution shoe, while the shoe C which is ordinarily the caution shoe will become the clear shoe. Furthermore, when the locomotive is backing, the mechanical circuit breaker A will be swung in the reverse direction to what it ordinarily is and, therefore, will not break the circuit, while the circuit breaker A', swinging in the reverse direction, will break the circuit.

From the foregoing description, it will be clear that we have provided a block signal system in which a danger signal, which is the most urgent signal for which the system is adapted, is given at the entrance of each block, although, under normal conditions, this signal will immediately be followed by a clear signal. It will further be clear that all active circuits are closed circuits and the giving of various signals is not dependent, in the first instance, upon closing of one or more normally open circuits, but upon the opening of a normally closed circuit. The brake actuating mechanism and speed governing device, assuming the train is in condition to travel, are always included in a closed circuit, the opening of which is, in turn, controlled by one or another of a plurality of normally closed controlling circuits, each including the mechanical circuit breakers A and A'. Any opening of that controlling circuit which is active, either by operation of one of these mechanical circuit breakers; by running down of the battery; or by breaking any wire in the circuit, immediately results in the opening of the brake circuit and in consequent stopping of the train.

Furthermore, of course, any breaking 60 down of the brake controlling circuit, through breaking of one of its wires, or through failure of the speed governed mechanism, due to breaking of its drive belt, will at once cause an application of the 65 brakes and stopping of the train. There are

three brake controlling circuits, namely, the clear, caution and danger circuit and each of these circuits, when active, is controlled by a main controlling circuit which may be termed the clear, caution and danger controlling circuits. The wiring of these latter circuits is such that each includes its own clear, caution or danger relay and further such that failure of any relay to operate in the proper manner, under any circumstance, 70 will leave open whatever controlling circuit passes through it and will consequently keep open the brake circuit and cause stoppage of the train. The clear controlling circuit, which includes the clear relay, also includes the mechanical circuit breakers, either of which may break the circuit and this clear circuit is such that, although the mechanical circuit breakers, after once breaking it, may, and as a matter of fact do, immediately close, they cannot, of themselves, reclose the circuit which they control. This can only be done by what may be termed a clear pick up circuit which includes not only the clear contact shoe of the train but also 80 must include a portion of an energized track circuit. In like manner, the caution relay, which is normally inactive, can be rendered active only by closing of a circuit through portions of an energized track circuit and a cab circuit. For this reason, the receipt of either a clear or a caution signal is a test of the track signal system, as well as of the cab signal system. One or the other of these tests is assured at the entrance 90 of each block or the train will be stopped as the danger signal is always given at the entrance of each block and the brakes can be released only by the immediate receipt of a clear or caution signal or by a 100 direct act upon the part of the engineer. The provision of the speed governed mechanism or circuit breaker permits the engineer to run his train at as slow speed as he wishes under any conditions which may 110 occur, but absolutely limits the height of speed at which he may drive the train under whatever conditions may exist.

It will of course be understood that the speed controlled circuit breaker, electrically 115 controlled valve mechanism, mechanical circuit breakers and closures and pole changer, illustrated and described in this case, do not, in themselves, constitute any part of our present invention, our invention consisting 120 merely in utilizing them in the manner set forth in connection with the circuits of the cab signal system. Any one of the above described elements may, therefore, be changed in its construction as deemed advisable, without departing from the spirit of our invention. Furthermore, we do not wish to limit ourselves to the specific wiring illustrated and described as such wiring might, of necessity, be changed somewhat 130

to adapt the system to use with different track systems or with different types of electrically controlled valve mechanisms, speed governed mechanisms and the like. Also, it will be evident that by the use of the terms "train" and "vehicle" in the specification and claims, we intend to cover any vehicle or connected group of vehicles operating over the tracks, such as a locomotive, a locomotive and its tender or a locomotive, tender and one or more cars. For these reasons we reserve the right to make any changes within the scope of the appended claims, which may seem advisable, at any time.

Having thus described the invention, what is claimed as new is:

1. In a block signal system, an electrical valve mechanism adapted, when energized, to be closed, a plurality of circuits through said mechanism, means in each circuit for closing its circuit, and a plurality of controlling circuits for closing such circuits, said controlling circuits being so arranged that 25 but one of them can be closed at any given time.

2. A block signal system including a mechanical circuit breaker, a clear contact shoe, a caution contact shoe, an electrical brake controlling mechanism, a normally energized clear relay, a caution relay, a circuit normally closed through the clear relay and brake controlling mechanism, a second circuit normally closed through the circuit breaker and the clear relay, means for energizing the caution relay, and a circuit through the clear relay, caution relay and brake controlling mechanism, said circuit being open in the clear relay when the clear 40 relay is energized and in the caution relay when the caution relay is deenergized.

3. A block signal system including a mechanical circuit breaker, a clear contact shoe, a caution contact shoe, an electrical brake controlling mechanism, a normally energized clear relay, normally deenergized caution and pick up relays, a circuit normally closed through the clear relay and brake controlling mechanism, a second circuit normally 45 closed through the circuit breaker and the clear relay and energizing the latter, a circuit including the clear relay and clear contact shoe and adapted to be closed by engagement of an energized track contact with the clear shoe, a circuit through the caution relay and caution contact shoe adapted to be energized by engagement of the caution shoe with an energized track contact, a circuit 50 through the clear relay and caution relay and brake controlling mechanism adapted to be closed upon deenergization of the clear relay and energization of the caution relay, a manually operable circuit closer, a circuit 55 through the clear relay, caution relay, pick up relay, brake controlling mechanism and manually operable circuit closer adapted to be closed by closing of the manually operable circuit closer when the clear relay is deenergized and the caution relay deenergized, a circuit through the pick up relay and brake controlling mechanism adapted to be closed by energization of the pick up relay, and means for causing the clear shoe to act 60 as a caution shoe and for causing the caution shoe to act as a clear shoe.

4. In a block signal system, the combination with a vehicle and a brake controlling mechanism, of a track controlled clear signal, a track controlled caution signal, a danger signal controlled by a closed circuit including a mechanical circuit breaker operable by a track trip, means for actuating the brake controlling mechanism to apply the 65 brake upon receipt of a danger signal, means for actuating the brake controlling mechanism to release the brake upon receipt of a caution or clear signal, and means controlling the speed of the vehicle under any 70 signal.

5. In a block signal system, the combination with a vehicle and a brake controlling mechanism, of a track controlled clear signal, a track controlled caution signal, a danger signal controlled by a closed circuit operable by a track trip, means for actuating the 75 brake controlling mechanism to apply the brake upon receipt of a danger signal, and means for actuating the brake controlling mechanism to release the brake upon receipt of a caution or clear signal, and means controlling the speed of the vehicle under any 80 signal.

6. In a block signal system, the combination with a vehicle and a brake controlling mechanism, of a track controlled clear signal, a track controlled caution signal, a danger signal controlled by a closed circuit including a mechanical circuit breaker operable by a track trip, means for actuating the 85 brake controlling mechanism to apply the brake upon receipt of a danger signal, and means for actuating the brake controlling mechanism to release the brake upon receipt of a caution or clear signal, and means controlling the speed of the vehicle under any 90 signal.

- means for actuating the brake controlling mechanism to release the brake upon receipt of a caution or clear signal, and means controlling the speed of the vehicle under any signal, said means including a plurality of brake mechanism controlling circuits, each having a distinctive contact and all having a common speed governed movable contact co-acting with the distinctive contacts, each 10 circuit including the brake actuating mechanism.
7. In a block signal system, the combination with a vehicle and a brake controlling mechanism, of a track controlled clear signal, a track controlled caution signal, a danger signal controlled by a closed circuit including a mechanical circuit breaker operable by a track trip, means for actuating the brake controlling mechanism to apply the 15 brake upon receipt of a danger signal, means for actuating the brake controlling mechanism to release the brake upon receipt of a caution or clear signal, and means controlling the speed of the vehicle under any signal, said means including a plurality of brake mechanism controlling circuits, each having a distinctive contact and all having a common speed governed movable contact co-acting with the distinctive contacts, each 20 circuit including the brake actuating mechanism and each circuit, when closed, being grounded to the driving mechanism of the movable contact, whereby failure of the driving mechanism will break the circuit.
- 30 8. In a block signal system, the combination with a track having clear and caution contacts, and means for rendering active the clear contact upon the absence of a train within a predetermined distance and 35 for rendering active the caution contact upon the presence of a train on the track ahead within a predetermined distance, of a vehicle having a clear shoe and a caution shoe adapted to engage the contacts, a brake controlling mechanism, a circuit normally closed through such mechanism controlling the brake, a mechanical circuit breaker operable to open the circuit to actuate the mechanism to apply the brake, and means 40 operable upon engagement of either the caution or clear shoe with its respective contact when active for actuating the mechanism to release the brake if previously applied.
- 45 9. In a block signal system, the combination with a track divided into blocks, of a train moving over the track, an electrically operated brake controlling mechanism on the train, means for actuating such mechanism to apply the brakes at the entrance of each block of the track unless a signal proper to the condition of the block is received, means for immediately giving a clear or a caution signal unless another train is 50 within a predetermined distance, means upon receipt of either a clear or a caution signal for actuating the brake controlling mechanism to prevent application of the brakes to permit movement of the train under a clear or caution signal, manually controlled means for actuating the brake controlling mechanism to release the brakes to run under a danger signal if the clear or caution signal is not received, and means for limiting the speeds at which the train can be run under the various signals. 75
- 55 10. In a block signal system, the combination with a track divided into blocks, of a train moving over the track, an electrically operated brake controlling mechanism on the train, means for actuating such mechanism to apply the brakes at the entrance of each block of the track unless a signal proper to the condition of the block is received, means for immediately giving a clear or a caution signal unless another train is 80 within a predetermined distance, means upon receipt of either a clear or a caution signal for actuating the brake controlling mechanism to prevent application of the brakes to permit movement of the train under a clear or caution signal, manually controlled means for actuating the brake controlling mechanism to release the brakes to run under a danger signal if the clear or caution signal is not received, and means for limiting the speeds at which the train can be run under the various signals, said means being such that the train cannot be run after a danger signal unless it first receives a clear or caution signal or unless it 85 is first brought to a complete stop.
- 60 11. In a block signal system, the combination with a vehicle, of a brake actuating mechanism, track controlled clear, caution and danger signals, means operable upon receipt of a danger signal for operating the brake actuating mechanism to apply the brake, and means controlling the speed of the vehicle under any signal, including clear, caution and danger circuits, to all of which 90 the brake actuating mechanism is common. 105
- 65 12. In a block signal system, the combination with a vehicle, of a brake actuating mechanism, track controlled clear, caution and danger signals, means operable upon receipt of a danger signal for operating the brake actuating mechanism to apply the brake, and means controlling the speed of the vehicle under any signal, including clear, caution and danger circuits, to all of which 110 the brake actuating mechanism is common, each of such circuits being active only when its corresponding signal is active. 115
- 70 13. In a block signal system, the combination with a track divided into blocks, of a vehicle moving over the track, an electrically operated brake controlling mechanism on the vehicle, means for actuating such mechanism to apply the brakes at the entrance of each block of the track unless a signal 120 125 130

proper to the condition of the block is received, means for giving a signal proper to the condition of the block, means operable upon the receipt of such a signal to prevent application of the brakes unless the condition of the block is dangerous, and means operable manually for releasing the brakes even when the condition of the block is dangerous, said latter means being operable only after the vehicle has been brought to a stop and permitting only a predetermined vehicle speed.

14. In a block signal system, the combination with a track divided into blocks, of a vehicle moving over the track, an electrically operated brake controlling mechanism on the vehicle, means for actuating such mechanism to apply the brakes at the entrance of each block of the track unless a signal proper to the condition of the block is received, means for giving a signal proper to the condition of the block, means operable upon the receipt of such a signal to prevent application of the brakes unless the condition of the block is dangerous, and means operable manually for releasing the brakes even when the condition of the block is dangerous, said latter means being operable only after the vehicle has been brought to a stop and permitting driving of the vehicle only up to a certain speed, and means for rendering the brake releasing means inactive upon receipt of a signal indicating a non-dangerous block.

15. In a block signal system, the combination with a track divided into blocks, of a train moving over the track, an electrically operated brake controlling mechanism on the train, clear and caution signals controlled thereby, means for actuating such mechanism to apply the brakes at the entrance of each block of the track unless a signal proper to the condition of the block is received, and means for immediately thereafter actuating such mechanism to prevent application of the brakes and to give a clear or a caution signal unless another train is within a predetermined distance.

16. In a block signal system, the combination with a track divided into blocks, of a train moving over the track, an electrically operated brake controlling mechanism on the train, clear and caution signals controlled thereby, means for actuating such mechanism to apply the brakes at the entrance of each block of the track unless a signal proper to the condition of the block is received, means for immediately thereafter actuating such mechanism to prevent application of the brakes and to give a clear or a caution signal unless another train is within a predetermined distance, and manually controlled means for releasing the brakes to run under a danger signal if the clear or caution signal is not received.

17. In a block signal system, the combination with a track divided into blocks, of a train moving over the track, an electrically operated brake controlling mechanism on the train, clear and caution signals controlled thereby, means for actuating such mechanism to apply the brakes at the entrance of each block of the track unless a signal proper to the condition of the block is received, means for immediately thereafter actuating such mechanism to prevent application of the brakes and to give a clear or a caution signal unless another train is within a predetermined distance, manually controlled means for releasing the brakes to run under a danger signal if the clear or caution signal is not received, and means for limiting the speed at which the train can run after the brakes have been so released manually.

18. In a block signal system, a brake controlling valve, an electrical mechanism adapted when energized to hold the valve closed, a plurality of circuits through said mechanism, means in each circuit for closing its circuit, and a plurality of controlling circuits for closing the first circuits.

19. In a block signal system, an electrical brake governing mechanism, a multi-branched brake governing circuit through said mechanism having one branch normally closed, a normally closed circuit controlling the opening of the first circuit, a trip operated mechanical circuit breaker in the second circuit, and means operable under certain conditions for creating one or another substitute controlling circuits to maintain and control one or another of the branches of the brake governing circuit during such time as the normal controlling circuit is open.

20. In a block signal system, an electrical brake governing mechanism, a multi-branched closed brake governing circuit through said mechanism having one branch normally closed, a normally closed circuit controlling the opening of the first circuit, a trip operated mechanical circuit breaker in the second circuit, means operable under certain conditions for creating one or another substitute controlling circuits to maintain and control one or another of the branches of the brake governing circuit during such time as the normal controlling circuit is open, and manually operable means for creating a substitute brake governing circuit when all of the first mentioned circuits are open.

21. In a block signal system, an electrical brake governing mechanism, a normally closed brake governing circuit through said mechanism, a normally closed circuit controlling the opening of the first circuit, a trip operated mechanical circuit breaker in the second circuit, means operable under cer-

- tain conditions for creating one or another substitute controlling circuits to maintain and control the brake governing circuit during such time as the normal controlling circuit is open, manually operable means for creating a substitute brake governing circuit when all of the first mentioned circuits are open, and a speed governed circuit breaker common to all of the brake governing circuits. 10
22. In a block signal system, an electrical brake governing mechanism, a normally closed brake governing circuit through said mechanism, a normally closed circuit controlling the opening of the first circuit, a trip operated mechanical circuit breaker in the second circuit, means operable under certain conditions for creating one or another substitute controlling circuits to maintain and control the brake governing circuit during such time as the normal controlling circuit is open, manually operable means for creating a substitute brake governing circuit when all of the first mentioned circuits are open, and a speed governed circuit breaker common to all of the brake governing circuits, the relation between the speed governed circuit breaker and the manually operable means being such that the latter can operate only when the speed governing means is in a predetermined condition. 20
23. In a block signal system, the combination with a track having clear and caution contacts, and means for rendering active the clear contact upon the absence of a train within a predetermined distance and for rendering active the caution contact upon the presence of a train within a predetermined distance, of a vehicle having a clear shoe and a caution shoe adapted to engage the contacts, a brake controlling mechanism, a circuit normally closed through such mechanism controlling the brake, a mechanical circuit breaker operable to open the circuit to actuate the mechanism to apply the brake, means operable upon engagement of either the caution or clear shoe with its respective contact when active for actuating the mechanism to release the brake if previously applied, and manual means for releasing the brake if not released by the previously mentioned means, the manual means being operative only when the vehicle is at a stop. 40
24. In a block signal system, the combination with a track having clear and caution contacts and a trip, of a vehicle, a brake controlling means on the vehicle, a multiple speed controlled circuit breaker on the vehicle, a plurality of circuits through the brake controlling mechanism and speed controlled circuit breaker, each being adapted to be opened by the circuit breaker at a different vehicle speed, a common source of energy for these circuits carried by the vehicle, a controlling circuit normally rendering one of the first mentioned circuits active and the others inactive, a circuit breaker in the controlling circuit adapted to be opened by engagement with the trip, and additional controlling circuits for again rendering the first controlling circuit active or for rendering another of the speed controlled circuit breaker's circuits active, the additional controlling circuits being without a source of local energy and being completed only through engagement with energized track contacts. 65 70 75
25. In a block signal system, a brake controlling mechanism adapted when deenergized to apply the brake, a multiple speed controlled circuit breaker including a movable contact member and a plurality of contact members over which it moves so arranged that it will successively move out of engagement with them as the speed increases, a plurality of circuits, one for each of the last contacts and each including the brake controlling mechanism, and track condition controlled means preventing more than one of such circuits being active at a time and determining which circuit shall be active under an existing track condition. 80 85 90
26. In a block signal system, a brake controlling mechanism adapted when deenergized to apply the brake, a multiple speed controlled circuit breaker including a movable contact member and a plurality of contact members over which it moves so arranged that it will successively move out of engagement with them as the speed increases, a plurality of circuits, one for each of the last contacts and each including the brake controlling mechanism, track condition controlled means preventing more than one of such circuits being active at a time and determining which circuit shall be active under an existing track condition, and a drive mechanism for the speed controlled circuit breaker, the drive mechanism being common to all of the circuits controlled by the speed controlled circuit breaker, whereby failure of the drive mechanism will cause application of the brake. 95 100 105 110
